UNITED STATES PATENT OFFICE.

GEORGE C. THOMPSON, OF SALT LAKE CITY, UTAH.

VEHICLE TONGUE-PLATE.

SPECIFICATION forming part of Letters Patent No. 729,810, dated June 2, 1903.

Application filed March 4, 1903. Serial No. 146,194. (No model.)

To all whom it may concern:

Be it known that I, GEORGE C. THOMPSON, a citizen of the United States, residing at Salt Lake City, in the county of Salt Lake and State of Utah, have invented certain new and useful Improvements in Vehicle Tongue-Plates; and I do hereby declare the following to be a full, clear, and exact description of the invention, such as will enable others skilled in the art to which it appertains to make and use the same.

My invention relates to means employed in attaching the doubletree to the tongue of a vehicle and for all similar purposes.

15 In ordinary couplings the king-bolt and the edge of the tongue-plate are rapidly worn away by frictional contact with each other; and it is an object of this invention to render these parts very greatly more durable in all 20 cases and stronger to stand any unusual strain that may be put upon them.

The accompanying drawings illustrate the invention, Figure 1 being a plan view of the device in operative position, Fig. 2 a plan of 25 the same detached, and Fig. 3 a side view in operative position and partly in section. Fig. 4 is a side view detached from the tongue, and Fig. 5 is a plan of a modification of the device.

30 Like letters of reference denote corresponding parts in the several views.

The letter A indicates a wagon-tongue, and B the doubletree, both shown fragmentarily. These parts are of the well-known shape com-

35 mon to draft-wagons and have the usual holes for an ordinary king-bolt or hammer b.

C is a curved arm or brace, pivoted on the tongue behind the plate and perforated at its upper end to admit the king-bolt, which is 40 supported by it.

D is the tongue-plate. Its body-surface is flat or made to conform to the upper side of the tongue, upon which it is secured by nails or screws through holes provided therefor.

45 d is a projection or bearing-surface for the

king-bolt on the under side of plate D, which I will designate as a "guard." It is adapted to enter and occupy the front side of the king-bolt hole a. This guard d is formed integrally with the body of the plate D by cutting three sides of a quadrangle through plate D 50 and bending down to a right angle at the uncut end the portion as cut through. This guard d may be made of any desired length and may be cut either from the central part of the plate D or from one side of it, as shown in Fig. 5. The guard d should be curved also to conform to the curvity of the hole a and of the king-bolt b.

By the use of this device I avoid at the bolt-hole the sharp edge of the common tongue-plate, which when in use continually cuts the king-bolt and is in turn worn rapidly away by the friction of the king-bolt, which also wears with equal certainty the doubletree 65 itself.

This device is very easily and cheaply made at any smith's shop, and its value is apparent in prolonging the usefulness of the parts protected by it, as well as in giving to them additional strength and stability. 70

Having now described my invention, what I claim is—

1. A vehicle tongue-plate having a body attachable to the tongue, at the king-bolt hole, 75 and a part of said body cut therefrom and bent to enter said king-bolt hole, to form a guard for said king-bolt, substantially as herein set forth.

2. In a vehicle tongue-plate, having a body attachable to the tongue, a part of said body cut therefrom, bent to enter the king-bolt hole and curved to conform to the curvity of said hole, for the purposes specified. 80

In testimony whereof I affix my signature 85 in presence of two witnesses.

GEORGE C. THOMPSON.
